US0D1112783S

(12) **United States Design Patent** (10) **Patent No.:** **US D1,112,783 S**
(45) **Date of Patent:** **** Feb. 10, 2026**

(54) **LIGHT THERAPY DEVICE**

(71) Applicant: **SHENZHEN KAIYAN MEDICAL EQUIPMENT CO., LTD**, Shenzhen (CN)

(72) Inventor: **Alain Dijkstra**, Amstelveen (NL)

(73) Assignee: **Shenzhen Kaiyan Medical Equipment Co., Ltd.**, Shenzhen (CN)

(**) Term: **15 Years**

(21) Appl. No.: **29/933,462**

(22) Filed: **Mar. 20, 2024**

(51) LOC (15) Cl. **24-01**

(52) U.S. Cl.

USPC **D24/209**

(57) **CLAIM**

The ornamental design for a light therapy device, as shown and described.

DESCRIPTION

FIG. 1 illustrates a front perspective view of a light therapy device;

FIG. 2 illustrates a front view of the light therapy device thereof;

FIG. 3 illustrates a back view of the light therapy device thereof;

FIG. 4 illustrates a left side view of the light therapy device thereof;

FIG. 5 illustrates a right side view of the light therapy device thereof;

FIG. 6 illustrates a top view of the light therapy device thereof;

FIG. 7 illustrates a bottom view of the light therapy device thereof; and,

FIG. 8 illustrates a back perspective view of the light therapy device thereof.

The broken lines in the drawings illustrate portions of the light therapy device that form no part of the claimed design.

1 Claim, 8 Drawing Sheets
